MAGNETIC COILS

John J. Glowacki, Plainville, Walter R. Munson, Kensington, and Earl D. Brightman, Bristol, Conn., assignors to The Sessions Clock Company, Forestville, Conn., a corporation of Connecticut

Application June 25, 1956, Serial No. 593,707

9 Claims. (Cl. 317—158)

This invention relates to magnetic coils and methods of manufacturing same, and it relates more particularly to magnet coils for small synchronous electric motors which may be used for instance in electric clocks, time control mechanisms and the like.

Such coils are generally bobbin-wound, the conventional bobbin normally consisting of a core portion and a pair of flanges at either end of the core, the coil being wound in the space between the flanges. The ends of the wire are ordinarily then soldered to the ends of short lengths of lead wire which are connected by suitable means to a power supply cord when the coil is installed in the motor. In coils of this type, the solder connections between the ends of the coil wire and the lead wires must be carefully taped with insulating tape and the whole outer surface of the coil covered with insulating tape. Moreover, the lead wires must be carefully secured mechanically to the coil so that the delicate solder connections to the extremely fine coil wire will be adequately protected.

Coils made in this manner require highly skilled personnel to assemble them. For one thing, where the leading end of the wire in the coil is brought out along the inner surface of one of the flanges of the bobbin, it must be fed under a paper washer and between the paper washer and the flange of the bobbin before the coil is wound. This is difficult to do in small coils because there is not enough room between the flanges of the bobbin for the operator's fingers. Furthermore, the washer must necessarily fit rather closely around the core of the bobbin leaving very little space through which to thread the end of the wire. On the other hand, if the end of the wire is led out through an aperture at the base of the flange, as is done in certain cases, it is even more difficult and requires still greater skill for the operator to thread the end of the extremely fine wire through such aperture.

The finishing operations in the manufacture of prior coils, that is, the operations subsequent to the winding operation, likewise require highly skilled operators to solder the fine coil wire to power terminals or leads and to carefully wrap and insulate the solder connection and coil in order to comply with strict underwriter's requirements. Since the soldering and taping operations required in such prior designs are not capable of being done by machine, it has been necessary in most instances to employ highly skilled personnel to do this work by hand, not to mention the considerable time and great pains which must be taken to train workers to do these finishing operations properly in order to prevent loss through a high percentage of rejected coils. This necessarily has kept the cost of the coils high.

Since the coil in small synchronous electric motors represents about 40% of the total manufacturing cost of the motor, any reduction in the cost of the coil means a large savings in the motor as a whole. It is an important object, therefore, of this invention to reduce the manufacturing costs of electric coils by providing

2

methods of assembly which eliminate the difficult hand operations heretofore required and by designing a novel coil construction which is readily adaptable to fabrication by machine, and in fact to complete automation, if desired.

A coil in accordance with the invention consists in general of a bobbin, onto which is wound magnetic wire, a cover being provided for the bobbin and a pair of terminals supported by the cover and the bobbin. The ends of the wire coil are fixed to the terminals which are held firmly between the bobbin and cover. Portions of the terminals project from the coil assembly so that a power cord from an electric power supply can be connected directly to the terminals at the coil by means of a simple solderless connection.

Heretofore, due to the necessity for insulating either the outer surface of the coil itself or the wire leads to which the ends of the coil wire are soldered, it has been found necessary to wrap the coil and/or the connections between the lead wires and the ends of the coil with an insulating tape after the bobbin is wound. The labor and material required in such finishing operations constitute a relatively large proportion of the total cost of manufacturing the coil. As will become more apparent hereinafter, the present coil construction and methods of manufacturing it not only eliminate the difficult manufacturing operations and therefore reduce cost, but also provide a completely sealed and insulated coil which is superior to prior coils in many ways.

An important advantage of the present coil is that it eliminates the wire leads which have usually been provided heretofore in small magnetic coils and which dangle uncontrolled from the side of the coil. In place of these leads, has been provided a terminal block, which renders the coil more compact and more readily adaptable for use in machines which assemble them in the motors and other electrical devices in which they are ultimately to be used.

Another object of the invention is to provide a coil, especially one in which a very fine wire is used, wherein the delicate terminal-ends of the coil are fixed to a more rugged connecting means so that the coil may be reliably connected to a suitable source of electric current in a simple expeditious manner.

These and other objects of the invention, as well as novel features and advantages, will become further apparent from the following description.

In the accompanying drawings in which specific illustrative examples of the invention are shown:

Fig. 1 is a view in top plan of a coil assembly embodying the present invention;

Fig. 2 is a view in side elevation of the coil assembly;

Fig. 3 is a view in end elevation of the coil assembly;

Fig. 4 is a view in section taken along line 4—4 of

Fig. 1;

Fig. 5 is a view in section taken along line 5—5 of Fig. 1;

Fig. 6 is a view in section taken along line 6—6 of Fig. 1;

Fig. 7 is a view in plan of the coil, terminals, and bobbin with the cover removed;

Fig. 8 is an exploded view in perspective illustrating the manner in which the terminals are fixed in the assembly;

Fig. 9 is a view in section through a coil winding arbor showing a preliminary step in winding the coil, according to the novel winding method of the invention;

Fig. 10 is a view similar to Fig. 9 showing another preliminary step in winding the coil;

Fig. 11 is another view like Fig. 9 but showing two

bobbins positioned on the winding arbor ready to start winding;

Fig. 12 is a view in section taken along line 12—12 of Fig. 11 but showing the wire wrapped around the bobbin after at least one complete turn of the winding arbor; and

Fig. 13 is a more or less diagrammatic view in front elevation of apparatus for welding the ends of the wire to the terminals.

Referring now to the drawings, and more particularly to Figs. 1, 2 and 6, the coil assembly is basically comprised of a bobbin 20 and a cover 21. The bobbin 20 consists of a hollow cylindrical core or wall 22 and annular flange 23 formed as an integral continuation from one marginal edge of wall 22. The relative disposition of the core and flange is 90° as will be appreciated. The other marginal edge of the wall 22 is formed of reduced section to define a projecting lip 24 and an outer shoulder 25. On one side of the flange 23 extending integral therewith and in spaced relation are a pair of leg portions 26 (see Figs. 7 and 8). A plate portion 27 formed integral with the leg portions 26 extends across the leg portions 26. Plate portion 27 is thicker than leg portions 26 defining shoulders 28 and 29, respectively, on the upper and lower sides thereof. The curved inner edge 30 of plate portion 27 is concentric with the outer edge of flange 23 and defines therewith an elongated slot 31 between leg portions 26. A dowel hole 32 is located approximately at the mid-point of plate portion 27 for reception of a dowel pin to be described hereinafter. A pair of slots 33 in flange 23 extend outwardly along the center of leg portions 26 into plate portion 27, terminating short of the outer edge of portion 27. As may be seen in Fig. 5, the outer ends of slots 33 within the plate portion 27 are deeper than the inner sections of these slots for a purpose which will be readily apparent hereinafter. In addition, the outer edge of plate portion 27 is provided with a pair of projections 35 which are used for means to which to secure the ends of the coil during the manufacture of the coil assembly. In the specific illustrative example here disclosed, the bobbin 20 is provided with a second flange 34 which fits on the reduced section 24 of the core 22 and is cemented thereto.

The cover of the coil assembly is made as a single piece and consists of a cylindrical wall 40 with a radially inwardly projecting flange 41 formed integrally from one marginal edge thereof. The other marginal edge of the wall 40 has formed integrally therewith a radially outwardly projecting flange 44. Spaced around the periphery of the wall 40 are a series of ribs 45 formed integral with the wall 40 and flange 44. The ribs 45 are disposed at 90° intervals around the wall 40 and, as will be appreciated, function as reinforcing means for the cover.

Projecting in spaced relation from one side of the wall 40 are a pair of leg portions 46 which are spaced apart by the same distance as the leg portions 26 of the bobbin 20. Thus, when the cover is placed onto the bobbin, the two pairs of leg portions can be arranged in overlying registry. A plate portion 47 is formed integral with the leg portions 46 and defines shoulders 48 therebetween adapted to abut against shoulder 28 of plate portion 27 when the cover is placed onto the bobbin. Plate portion 47 is further characterized by a curved edge 49 facing flange 44 and concentric therewith, such that the marginal edge of the flange 44 between leg portions 46 defines with the curved edge 49 of the plate portion 47 an elongated slot 50 which coincides with slot 31 in the bobbin. Extending from wall 40 and integral with leg portions 46 are channel section bar portions 51, within which are formed slots 52 that are open on the underside of plate 47 and extend inwardly along legs 46 and through the flange 44 into the space within the cylindrical wall 40, as best seen in Fig. 8. Formed at the ends of the bar portions 51 are a pair of recessed socket portions 53, each having a cylindrical recess 54 on the upper side which communicates with the slot 52 through a rec-

tangular opening 55 at the base of the recess. As may be seen in Figs. 4 and 8, the outer ends of slots 52 adjacent openings 55 are enlarged and taper upwardly to openings 55 for a purpose which will be explained hereinafter. A rib portion 57 connects the socket portions 53 and serves as a reinforcement. Formed on the underneath surface of plate portion 47 is a centering or dowel pin 58 adapted to be received in the hole 32 defined in the plate 27 of the bobbin.

Received in the slots 33 on bobbin 20 are terminals 70. Each terminal 70 is made as a substantially L-shaped metal blade with a base section 71 constituting the heel of the L, a terminal section 72 constituting one leg and an inwardly extending section 73 constituting the other leg. Leg 72 is notched as indicated at 74 and 75 where it joins with heel 71, and heel 71 is notched as indicated at 76 for purposes which will be described hereinafter. The heel 71 is of greater depth than the inwardly extending leg 73 forming therewith a shoulder 77. The terminals 70 fit with a press fit into slots 33 in bobbin 20 with the heel sections 71 extending down into the deeper sections of slots 33 in the plate portion 27, the shoulder 77 of terminal 70 abutting a shoulder 78 (Fig. 5) in the bottom of slot 33. As may be best seen in Fig. 8, the lower corner of the end of leg 73 is notched at 79 in such a way that when the terminal 70 is seated in slot 33, the upper edge of notch 79 is spaced from the surface of flange 23 of the bobbin leaving room for one end of the coil wire to be engaged in notch 79 as shown in Fig. 5.

When the cover 21 is placed on the bobbin with the terminals in position in the terminal plate 27, the upper edges of legs 73 of the terminals fit into the slots 52 in the cover, and the terminal sections 72 project through openings 55 into and beyond socket portions 53 where they are readily accessible for connection with female terminal connectors provided on a power supply cord (not shown).

A coil of wire 60 is wound on the bobbin between the integral or first flange 23 and the second flange 34. One end of the wire 61 (Fig. 7) at the bottom of the coil passes under the inner edge of a paper washer 62, which is positioned on the core 22 next to flange 23 and insulates the end section 61 of the coil from the rest of the coil. Wire end 61, therefore, extends outwardly between washer 62 and flange 23, passes around the inner end of one of the terminals 70 engaging in notch 79, and along the outer side of the terminal where it is fixed thereto at 63. Similarly, the other end 64 (Figs. 6 and 7) of the coil 60, which of course extends from the outer layer of the coil, passes around the end of the other terminal 70 and is fixed thereto. While the tip ends of the wire are shown in Fig. 7 as extending beyond the end of terminal 70, actually in the finished coil these ends are cut or broken off at the outer end of the terminals. During manufacture of the coil, however, the ends of the coil are left long so that they can be held temporarily until they are permanently fixed to the terminals.

The ends 61 and 64 of the coil may be fixed to the terminals 70 in various ways. One method which has been found to be satisfactory is to weld the wire to the terminal at the point 63, using apparatus to be described hereinafter. On the other hand, the wire can be mechanically staked to the terminals by providing a groove (not shown) in the side of the terminal in which the wire is laid, and then by upsetting the metal on the terminal adjacent the wire. This method has a distinct advantage in that the insulating enamel on the wire does not have to be removed prior to staking the wire, whereas if the wire is welded or soldered to the terminal, the enamel should first be sanded off to ensure proper connection.

Another way in which the connection can be made is to remove the enamel insulation from a relatively long section adjacent the end of the wire and then to pass it 75 through notch 79, as before, and around through notch

76 at the outer end of the terminal, then to make several turns around the contact section 72 in notches 74 and 75 until the wire is secure. When the cover 21 is placed in position, the wire thus wrapped around section 72 of the terminal will be forced into engagement with the terminal by the walls of the opening 55 in the cover. Moreover, where the cover is made of cellulose acetate, a drop of a suitable acetone cement can be applied in the recess 54 after the cover has been assembled on the bobbin, and this will work its way through the opening 55 around the wire, causing the cellulose acetate bobbin or cover therefor to swell, thus forcing the wire into still more integral contact with the terminal. The acetone cement then quickly hardens ensuring a permanent connection. Or, if desired, instead of using the cement, a hot iron may be applied to the terminal block of the coil adjacent the socket portions 53 to cause deformation or swelling of the plastic casing around the connection in order to bind the wire and terminal in integral contact with each other.

Both the bobbin and cover can conveniently be made of a resinous plastic material, and thus these elements can be economically molded in large quantities. The precise materials which can be employed for the bobbin and cover are varied; however, the preferred materials in their order of preference are flame resistant cellulose acetate, tenite II which is a cellulose acetate-butyrate plastic molding compound made by the Eastman-Kodak Company, and nylon which is a polyamide type resin. It will be appreciated that whereas specific materials are mentioned above as preferred, other materials which are suitable are not necessarily precluded and any suitable material is within the purview of the present invention at least in its broadest aspects. The material of which the terminals 70 can be made may be any of the usual materials exhibiting good current carrying characteristics such as copper, brass, or aluminum.

It will be noted from the foregoing description of one particular construction of a coil embodying the invention that the flange 34 is not molded integrally with the rest of the bobbin 20. One reason for this is that it is less expensive to mold the core 22 and flange 23 in one piece and the flange 34 as a second piece than it is to mold a one-piece bobbin having two integral flanges. This is due to the fact that the two-flange bobbin must be made in a split mold.

Another and more important advantage of providing the bobbin with only one flange is to facilitate, and thus reduce the cost of, winding the bobbin. Accordingly, an important aspect of the present invention is found in the novel method of winding coils to be described hereinafter. The apparatus employed for winding the coils can be any suitable coil winding apparatus, as for example, the Universal Hi-Speed Coil Winder Model No. 102, as made by the Universal Winding Company of Providence, Rhode Island. The arbor of the apparatus, however, will necessarily be slightly modified in order to accommodate the device of the present invention. Reference is now had more particularly to Figs. 9 to 12, which show the steps in starting the novel winding operation. As will be evident, the winding arbor is designated by the numeral 80 and includes a shank or spindle 81 which terminates in a threaded section 82. Received on the threaded section 82 is a slotted washer 83 (Fig. 12) and nut 84 which bears against it. A flanged sleeve 85 will fit over nut 84 onto shank 81 when the slotted washer 83 is removed. In the particular example shown in the drawings, the winding arbor provides for winding two bobbins simultaneously. Consequently, the first sleeve 85 is positioned with its flange against the shoulder 86 formed by the shank 81, which is of smaller diameter than the rest of the arbor 80, and is keyed thereto as shown. Before sleeve 85 is mounted on the winding arbor, a bobbin 20 is placed on the sleeve and is fixed against rotation relative thereto by a pair of pins 87 75

projecting in spaced relation from the flange of sleeve 85 so as to fit into slot 31 of the bobbin and to rest against opposite ends thereof as shown in Fig. 12. At this point, the bobbin does not include the outer flange 34.

5 The bobbin and sleeve together are then placed on the shank 81 of the spinning arbor. The operator takes a paper insulating washer 62 and feeds the end 61 of the magnetic wire to be wound from a supply thereof (not shown) through the washer 62 before putting it on the 10 winding apparatus. With the wire thus looped through the washer 62, the latter is fitted over the shank 81 and onto the bobbin 20. Fig. 9 shows the washer 62 as it is being placed on the bobbin, and Fig. 10 shows the washer 62 in place with the end 61 of the wire extending 15 outwardly between the flange 23 of the bobbin and the washer 62. The free end of the wire is then fastened to the bobbin 20 by wrapping it around one of the projections 35 as shown in Fig. 10. Next, the operator takes a plastic washer 34, applies a liquid cement to its flange 20 34', fits this over the shank 81 of the winding arbor in the manner shown in Fig. 10 and places it on the lip 24 at the outer marginal edge of core 22 of the bobbin, on which it becomes permanently cemented while the bobbin is being wound.

25 A second bobbin 20 supported on another flanged sleeve 85 is placed up against the flange 34 of the first unit, and the end of a second wire started on that bobbin in exactly the same way as the first. After the flange 30 or plastic washer 34 for this second bobbin is put in place, the slotted washer 83 is slid onto threaded shank 82 between the outer end of the bobbin and the nut 84. The nut 84 is then quickly tightened down securing the two bobbins in place on the winding arbor as shown in Fig. 11.

35 The winding arbor is then rotated in order to wind the wire onto both bobbins simultaneously, a guide (not shown) being provided for the wire as it comes from the supply in order to lay it in even layers on the bobbins. The winding apparatus is set to automatically 40 wind exactly the desired amount of wire onto each bobbin. While the wire is being wound, the operator is free to start one or more similar sets of winding units in operation. When the bobbins are wound, the trailing portion of the wire to each bobbin is wrapped around 45 the other staking lug or post 35 and cut or broken from the source of supply. The nut 84 is then loosened and split washer 83 slid off the threaded end of the arbor. The wound bobbins may then be readily removed from the winding arbor, disconnected from the sleeves 50 85 and then placed on a traveling conveyor (not shown) along which various finishing operations are performed on each coil.

55 It should be noted that when the wound bobbin is removed from the winding machine, the free end of the wire is fastened firmly in place so that the coil will not unwind. Moreover, it is not necessary to disconnect the leading end 61 of the wire from any part of the winding apparatus as has been the case heretofore. Provision of the staking posts 35 on the bobbin greatly 60 facilitates handling the coil during the initial assembling operations thereof and is, therefore, an important feature of the novel construction of the present coil.

65 It will also be readily apparent from the foregoing that where a wire is used which is provided with a plastic washer or flange 34 may be omitted. So far, however, available wire of this kind is prohibitively expensive for use in coils for small inexpensive motors, such as clock motors. Nevertheless, the present coil construction which includes the flanged cover 21 makes it entirely possible to omit one of the flanges of the bobbin in certain instances, thereby greatly facilitating the winding of the coil as well as reducing the cost of the bobbin.

In finishing the coil, the following operations are

carried out: First the two terminals 70 are pressed into the slots 33 with their terminal sections extending away from the portion 27 of the bobbin. The enamel insulation on the ends 61, 64, of the coil is then removed in order to ensure proper electrical contact with the terminals 70, and the wires are led through notches 79 at the rear ends of terminals 70, along the outer sides of the terminals, through notches 76 at the front end, as shown in Fig. 7, and then wrapped around the upstanding section 72 of each terminal. If the wire is to be welded to the terminals 70, as has been found to be desirable, this is done next, and the cover 21 is then secured in place over the bobbin 20. This may be accomplished by applying an acetone cement to the cellulose acetate cover along the edge of flange 44 before the cover 21 is pressed onto the bobbin. However, if the coil is to be used in a motor or other device in such a way that the cover 21 and bobbin 20 are held together by the assembly in which it is ultimately used, it is only necessary to cement the terminal portions together to ensure that the connection between the ends of the coil and the terminals 70 are not disturbed. Thus, cement may be applied only to dowel pin 58 on the cover 21 so that this will become fixed in the hole 32 in the bobbin 20. In order to ensure that the wire ends 61 and 64 are not disconnected from the terminals 70 when the cover 21 is mounted, the slots 52 are cut away adjacent the points 63 where the connection is made. As shown in Fig. 4, this prevents the edge of slots 52 from scraping the wire off the terminal as the cover is pressed into place. After the cover is applied, the coil is tested in the usual way.

It will be readily observed from the foregoing that each finishing operation can be carried out by machine. For example, the terminals 70 may be pressed into the slots 33 in the wound bobbin by means of a press, to which the terminals and bobbins are fed either by hand or automatically. While it has not been found feasible to remove the insulation from the wire ends entirely by machine, this operation can be wholly eliminated by mechanically staking the wire to the terminals as suggested hereinbefore. It is also possible to test the coil at the same time that the cover is being applied by simply furnishing the cover assembling press with suitable contacts which engage the terminals 70 while the cover is being cemented to the bobbin, these contacts being connected to an ohm meter or other test instrument so that an operator attending the cover assembling press can also record the results of the tests on each coil. The foregoing illustrates the adaptability of the present coil to mass production methods and the substantial reduction in, or virtual elimination of, the need for skilled personnel to perform the finishing operations on the coil.

One of the finishing operations which requires great skill and which has therefore been felt to be almost indispensable, is the solder connection between the very fine wire of the coil and the more rugged contact, such as a power lead. The present coil construction makes possible the elimination of this soldering operation, which is difficult, if not impossible, to do by machine. Thus, as has been brought out hereinbefore, the method now being used for making this extremely delicate connection in the present coil is to weld the wire to the terminals by using apparatus shown more or less diagrammatically in Fig. 13.

The welding apparatus consists of a coil locating fixture 90 in which the wound bobbin 20 is held with the terminal sections 72 projecting upwardly. A central contact and hold-down member 91 is movable vertically as viewed in Fig. 13 by conventional power means (not shown) into position between terminals 70. The lower portion of contact 91 fitting between terminals 70 is of such a size as to just engage the inner surfaces of both the terminals. On both sides of the coil locating fixture

90 are guide members 92 having tracks 93 in their upper surfaces, within which terminal blocks 94 may slide laterally with respect to the central contact 91. Each terminal block 94 has a plunger 95 connected to a suitable power device, such as an air cylinder (not shown), for moving the blocks 94 toward and away from the central contact 91. Blocks 94 are also provided with welding points 96 projecting inwardly toward the central contact 91 where they may be moved into engagement with the ends 61 and 64, respectively, of the wire coil 60 which lay along the outer surfaces of terminals 70 on the wound bobbin 20. Welding points or lateral contacts 96 are furnished electrical power through high tension cables 97 which are connected thereto in any suitable manner indicated generally at 98, the points 96 and connections 98 being of course properly electrically insulated to prevent short circuit. High tension cables 97 are connected to suitable welding equipment (not shown) such as, for example, Raytheon Model 225 "Weldpower" Unit No. 1537, Equipment No. AL 101, 110 volt, 10 amperes, 60 cycle, single phase, manufactured by Raytheon Manufacturing Company. The central contact 91 is likewise connected to the welding equipment through a suitable connection which is not shown in the drawing.

In order to weld the ends 61, 64 of the coil wire to the respective terminals 70, the wound bobbin 20 is placed in the fixture 90 which holds it against movement laterally, the central contact 91 being in its raised position. The ends 61, 64 of the wire are at this point in the assembly wrapped around the terminal sections 72 and have had the enamel insulation removed therefrom as by sanding. With the bobbin in place, the ends of the wires are unwrapped from the sections 72 of terminals 70 and are held tautly in contact with the sides of the terminal, as shown in Fig. 13, with each wire engaged in both the rear notch 79 and the front notch 76 in order to accurately locate it at a point where it may be engaged by the welding point 96. The central contact 91 is then lowered between the terminals 70 and presses against the portion 27 of the bobbin holding it down and at the same time making contact with the terminals 70. The welding points 96 are then moved laterally inwardly until they engage the terminals 70 and wires 61 and 64, respectively, in order to weld the wires to their terminals.

When the weld has been made and while the bobbin is being held securely in place by the central contact 91, the ends 61 and 64 of the wire are broken off adjacent the forward end of terminals 70 as shown in Fig. 5. The central contact 91 is then retracted and lateral contacts or welding points 96 moved outwardly in opposite directions so that the bobbin 20 can be removed and another placed in the fixture 90. After the ends of the coil have been welded to the terminals as described above, it is thereafter only necessary to place the cover on the coil in the manner hereinbefore described.

Coils of the construction disclosed herein using semi-automatic assembling apparatus have been made in production for at least 25% less than it is possible to make a conventional double flanged coil having leads soldered to the ends of the coil and wrapped in insulating tape with reinforcing strips for the wire leads to protect the solder connection. The reduction in cost is even greater of course when compared with the cost to obtain such conventional coils on the market. Moreover, it is felt that, due to the particular design of the present coil, even greater reductions in cost can be effected by using automatic equipment for assembling the coil which would be impossible to use in manufacturing coils of prior designs.

70 What is claimed is:

1. In an electric coil, the combination comprising a bobbin of electrical insulating material including a cylindrical core portion, a flange formed integral with one marginal edge of said core portion and a terminal plate

portion formed integral with said flange, a cover of electrical insulating material fitting onto said bobbin and defining with said core portion and said flange an annular space completely enclosed thereby, said cover having a terminal plate portion arranged in overlying registry with the terminal plate portion of said bobbin, a pair of terminals supported by said terminal plate portions with each partly projecting through one of said plate portions, and a coil of wire located concentric with and in said annular space on said core portion with the free ends of said wire lying between said terminal plate portions and fixed to said terminals.

2. The combination defined in claim 1, wherein said terminal plate portions are rigidly cemented together.

3. In an electric coil, the combination comprising a 15 bobbin of electrical insulating material, a cover of similar material fitting thereon so as to define therewith an annular space within said bobbin, said bobbin having a flange forming one side of said annular space, a portion of said flange extending beyond the outer surface of said bobbin, said cover having a corresponding portion arranged in overlying registry with said portion of the bobbin flange whereby said portions together form a terminal block, a pair of terminal blades mounted between said bobbin and cover portions of said terminal block, and a 20 coil of wire concentrically located in said annular space with the free ends of said wire fixed to said terminal blades.

4. The combination defined in claim 3, which includes an insulating washer adjacent one side of said coil of 30 wire, one free end of said coil of wire projecting through said washer and extending along the side thereof remote from said coil of wire.

5. The combination defined in claim 3, wherein the free ends of said wire are welded to said terminal blades.

6. In an electric coil, the combination comprising a 35 bobbin of electrical insulating material having a cylindrical core, a first flange integral with said core at one end thereof, a terminal portion formed integral with said

5 flange, and a second flange at the other end of said core; a cover of material similar to that of said bobbin comprising a cylindrical wall fitting over said second flange with one edge of said cylindrical wall in contact with said first flange of said bobbin, an annular flange formed integrally with the opposite edge of said cylindrical wall and extending radially inwardly thereof in overlapping engagement with said second flange of said bobbin, and a 10 terminal portion arranged in overlying registry with the terminal portion of said bobbin; a pair of terminals supported by said terminal portions; and a coil of wire concentrically located in the annular space between said bobbin and said cover with the free ends of said wire lying between said terminal portions and fixed to said terminals.

7. The combination defined in claim 6, in which said terminals are metal blades mounted in corresponding grooves in said terminal portions, one of said terminal portions having an aperture for each terminal, a portion of each of said terminals projecting through said aperture for connection with an electric power supply.

8. The combination defined in claim 7, wherein said terminals project through the terminal portion on said cover, said terminal portions extending radially of said bobbin adjacent the said first flange thereof.

9. The combination defined in claim 8, wherein the ends of said wire are welded to said terminal blades.
